US0D1045397S

(12) **United States Design Patent** (10) Patent No.: **US D1,045,397 S**
(45) Date of Patent: ** Oct. 8, 2024

(54) **MULTIFUNCTIONAL STORAGE BOX**

(71) Applicant: **Hongyong Yu**, Guangdong (CN)

(72) Inventor: **Hongyong Yu**, Guangdong (CN)

(73) Assignee: **SHENZHEN GULI Technology Co., Ltd.**, Guangdong (CN)

(**) Term: **15 Years**

(21) Appl. No.: **29/760,484**

(22) Filed: **Dec. 1, 2020**

(30) **Foreign Application Priority Data**

Jun. 24, 2020 (CN) 202030333363.3

(51) LOC (14) Cl. **03-03**

(52) U.S. Cl.

USPC **D3/315**

(58) **Field of Classification Search**

USPC D14/447; D3/315, 206

CPC F16M 13/00; F16M 11/38

See application file for complete search history.

(57) **CLAIM**

The ornamental design for multifunctional storage box as shown and described.

DESCRIPTION

FIG. 1 is a front elevational view thereof;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof;
FIG. 7 is a perspective view of a multifunctional storage box showing my new design;
FIG. 8 is a perspective view of a multifunctional storage box showing our new design; and,
FIG. 9 is a perspective view of a multifunctional storage box showing our new design.

1 Claim, 8 Drawing Sheets

FIG. 1

FIG. 2

FIG. 3

FIG. 4

FIG. 5

FIG. 6

FIG. 7

FIG. 8

FIG. 9
